UNITED STATES PATENT OFFICE.

GEORGE E. ADAMS, OF NEW BRITAIN, CONNECTICUT.

DESIGN FOR A SUSPENDER-END BODY.

SPECIFICATION forming part of Design No. 33,065, dated August 14, 1900.

Application filed June 19, 1900. Serial No. 20,903. Term of patent 7 years.

To all whom it may concern:

Be it known that I, GEORGE E. ADAMS, a citizen of the United States, residing at New Britain, in the county of Hartford and State 5 of Connecticut, have invented and produced a new and original Design for a Suspender-End Body, of which the following is a specification, reference being had to the accompanying drawings, forming part thereof.

10 In the drawings, Figure 1 is a front elevation of the suspender-end body embodying the present design. Fig. 2 is a side elevation.

Like letters of reference in both figures indicate the same parts.

15 The leading or characteristic features of the present design are the body portion having the upwardly-extending circular plates at front and back with the circular-headed projection arranged centrally of the front plate

and the downwardly and outwardly curved 20 arms or branches joined to the plates by a narrow neck portion, each of the arms constituting a tubular extension.

The letters A and B represent the front and back plates, and C the headed projection extending from the back plate through the center of the front plate A.

C' C² represent the downwardly and outwardly curved tubular arms or branches, and E the narrow connecting neck portions between the plates and the arms or branches.

What I claim is—

The design for a suspender-end body as herein shown and described.

GEORGE E. ADAMS.
